GLOW DISCHARGE TUBING AND MEANS
FOR MOUNTING THE SAME

Hirsch Epstein, Chicago, Ill.

Application November 10, 1941, Serial No. 418,469

8 Claims. (CL. 176—122)

This invention relates to glow discharge tubing and to terminals and mountings therefor, and more particularly for fluorescent type tubing.

Fluorescent tubing generally consists of a transparent glass-like tube coated with the usual fluorescent chemicals and provided at each end with a terminal structure for extending the electric circuit to the tubing. The terminal structure, in one standard form of hot cathode type tube, consists of a short metal cap sealed to the end of the glass tubing and which cap has a pair of metal studs or plugs extending outwardly therefrom for receiving the electrical connections. The metal studs extend the circuit to a hot cathode within the tube. The metal studs are adapted to be received in a socket which may be of a well known construction. In the case of straight fluorescent tubes a socket at each end holds the tube against longitudinal movement and thus supports it in the socket. In the case of a curved tube, especially one, for instance, of a U-shape, the two ends of the tube are adjacent one another and therefore if the tube is to be held in other than in a position extending vertically upward from the sockets it is necessary that some means be provided for holding the tube against inadvertent retraction from the sockets.

It is one of the objects of the present invention to provide means which can be used in connection with standard types of fluorescent tube terminals for releasably locking the tube terminal to the socket and thus hold the tube in place. It is a further object of the present invention to provide such an arrangement wherein the amount of change that must be wrought in the standard tube or socket is reduced to a minimum. In accordance with one embodiment of the present invention this is accomplished by providing a slight change in the tube terminal and no change whatsoever in the socket. In accordance with the preferred embodiment of the present invention narrow slots are formed in the metal cap at the end of the fluorescent tube, which slots are adapted to receive the ends of a spring clip that is positioned to embrace the associated socket and thus hold the fluorescent tube against retraction.

Straight fluorescent tubes can be made in standard lengths so that there is practically no deviation between the lengths of different tubes. When this is the case the sockets for receiving the ends of a tube of a given standard length may be mounted in place the necessary fixed distance apart without any great difficulty. In the manufacture of curved fluorescent tubes the

locations of the terminals or caps of a tube, with respect to one another, cannot be gauged with as high a degree of precision as in the case of straight tubes. It is therefore necessary to mount at least one of the sockets for receiving the tube in such a manner that adjustments can be made in the relative positions of the two sockets to receive different tubes of the same so called standard size but which differ from one another an amount sufficient to require adjustments of the relative positions of the sockets. In accordance with the principles of the present invention one or both of the two sockets for receiving the two ends of a fluorescent tube is so mounted as to be adjustable. As a result the positions of the sockets can be adjusted with respect to one another to compensate for small differences in the relative locations of the two end caps of different curved tubes wherein the deviations are such as are normally encountered in the usual factory production methods.

It is a still further object of the present invention to provide means for locking and holding the end cap of a fluorescent tube with respect to the terminal socket so as to maintain contact between the prongs of the tube and the socket even though they are at a slight angle to one another.

The attainment of the above and further objects of the present invention will be apparent from the following specification taken in conjunction with the accompanying drawing forming a part thereof.

In the drawing:

35 Figure 1 is a perspective view showing the mounting of a U-shaped fluorescent tube;

Figure 2 is a fragmentary perspective view of the end of the tube of Figure 1;

Figure 3 is a fragmentary longitudinal sectional view taken through the end of the tube of Figure 1;

Figure 4 is a sectional view taken along the line 4—4 of Figure 1 and looking in the direction of the arrows;

Figure 5 is a section taken along the line 5—5 of Figure 4 and looking in the direction of the arrows;

Figure 6 is a view similar to Figure 2 and showing an alternative type of mounting for the socket;

Figure 7 is a perspective view of the spring clip used in the structure of Figure 1;

Figure 8 is a perspective view showing the manner of mounting and supporting the tube of Figure 1 in a horizontal position; and

Figure 9 shows how the present invention is applicable to tubing curved through an angle of approximately 90°.

Reference may now be had more particularly to the structure illustrated in Figure 1. In this figure 1 indicates a glow discharge fluorescent light which includes a glass tube circular in cross section and bent into a substantially U-shape. The tube is coated on the inside with the usual fluorescent materials, is provided with the usual hot cathodes at each end and the usual heating filaments 2 at each end as is known in the art. The tube is sealed, evacuated and filled with the proper gas or gases at the usual sub-atmospheric pressure, as is well known in the art. A metal cap 3 is cemented to each end of the tube, one said cap consisting of a small ring that fits over and is cemented to the end of the tube 1 and has a shallow peripheral groove 4 adjacent the end thereof. The cap also includes a disc 6 of insulating material held in place by the grooves 4 and an outer rim 7 of the cap. A pair of terminal prongs 8-8 extend through and are held by the disc 6. The terminal prongs are connected within the cap to wires that are sealed through the glass body of the tube and connect to the opposite ends of a heater or filament 2 for a hot cathode, which filament may constitute the cathode, all as is well known in the art. The fluorescent light of the present invention differs from standard type of commercial hot cathode fluorescent lights essentially only in that the glass tube is bent to a U-shape instead of being straight and, further, that the cap 3 differs from a standard cap in that a pair of narrow slots 9-9 are milled in the cap at opposite sides thereof in the groove 4.

Each cap 3 is adapted to be received in a standard type of socket, indicated at 10. The socket 10 has two slots 11-11 therein in which the terminal prongs 8-8 of the metal cap slide, said slots being bent at substantially right angles, as indicated at 12-12, in a manner well known in the art. The prongs 8 are releasably held in place by spring clips 13-13 in the socket, as is well known. The socket is of a standard well known construction and no novelty is claimed therein per se. In Figure 1 the sockets 10-10 have been mounted to receive a fluorescent tube extending downwardly therefrom. In order to prevent the tube from falling downward away from the socket, there is provided a spring metal clip 16 of a shape such as is shown more particularly in Figure 7. This clip consists of a back 17 having integral sides 18-18 which are inwardly flanged at 19-19. The free ends of the flanges 19-19 may be slightly curved, along a radius of approximately that of the cap 3, if desired. While the end of the tube is manually held in the socket 10 the clip is slipped over the back of the socket, the arms 18-18 are sprung apart slightly and then released to permit the flanges 19-19 to enter the slots 9-9 in the cap 3. The clip thus rests on the back of the socket and supports the tube against downward movement. The prongs 8-8 of the tube within the recesses 12 are thus also held against sliding out of the socket by way of the slots 11. It is thus apparent that each terminal end of the tube 1 is firmly held in its socket 10.

In those cases where the tubes 1 are of standard sizes so constructed that there is no deviation in the distances between the metal caps 3-3 of the tube the sockets may be mounted rigidly on the wall. In some instances, however, the devia-

tion in distances between the metal caps 3-3 of a non-straight tube are such that if the sockets 10-10 are rigidly supported at fixed distances apart the terminal prongs of the two ends of the tube will not be accurately opposite the terminal receiving slots 11-11 of the two sockets 10-10.

5 In such instance it is necessary to change the position of at least one of the sockets each time a tube 1 is replaced by another tube. 10 This difficulty is eliminated in accordance with the principles of the present invention by mounting one or both of the sockets in such a manner as to permit adjustment of the position of the socket.

15 A description will now be given of the manner of mounting the socket 10. The socket 10 itself is a standard socket consisting of a base 25 from which extends an upright 26, of rectangular cross section, the base and upright consisting of a single piece of insulation such as porcelain, Bakelite, or any other suitable insulation. The base 25 has a slot 27 extending therethrough at the forward edge thereof, and has two notches 28-28 formed therein for receiving the circuit 20 extending conductors. The circuit extends from the base through the upright 26 to terminals opposite the slots 12-12. In the present instance the base 25 of the socket 10 is mounted on the rear side of a supporting plate 30. The upright 26 extends through a hole 31 in the plate 30, the hole being slightly longer and slightly wider than the width and thickness of the upright 26 so that the upright has complete freedom of play both as to shifting and tilting while it extends through the hole 31. A thick soft rubber 25 plug or cushion 33 is interposed between the top surface of the base 25 and the plate 31. A screw 34 extends loosely through a slightly oversized hole in the plate 30, through the plug or cushion 33, through a washer 35 which bears against the base 25, and through the slot 27 and has a nut 38 threaded thereon and bearing against the bottom of the base. The screw 34 is tightened an amount sufficient to place the plug or cushion 33 under considerable pressure but still allow for a considerable possible increase of pressure. The socket 10 is thus held in position on the wall 30 and yet is adjustable angularly up and down and from left to right in the oversized hole 31 while the screw 34 continues to hold the socket in place.

30 Thus if one of the metal caps 3 is out of relative position with respect to the other cap on the fluorescent tube the adjustable socket 10 can be shifted towards or away from the other 35 socket or can be shifted up or down angularly to bring it into proper position for receiving the terminal prongs 8-8 of the adjacent cap 3. In the preferred arrangement both sockets 10-10 are adjustably mounted so that any deviation in 40 proper alignment of the two metal caps is taken up by relative movement of both sockets whereby each socket need adjust for only half of the deviation. The spring clip 16 maintains the caps 3 in engagement with the sockets even though 45 there may be a small angle between the cap and the socket.

40 While I have shown the yielding plug or cushion 33 as located between the supporting plate 30 and the base 25 of the socket, it is within the purview of the present invention to mount the yielding means on the opposite side of the base 25 and the nut 38. This is illustrated in Figure 6. In this figure a small metal ring 46 having a rounded nose 47 is interposed between the

70

base 25 and the plate 30. The screw 34', which corresponds to the screw 34 of Figure 4, extends through the ring 40 and through the slot 27 in the socket 25, as before. The yielding means, in this instance is in the form of a coiled spring 43, and is interposed between the base 25 and the nut 38 that is threaded on the screw 34', a washer 44 being positioned between the nut 38 and the spring 43. The screw is tightened to place the spring 43 under pressure. It is thus apparent that the socket 10 of Figure 6 is universally adjustable in any direction by swiveling with the screw 34' in the same manner as is the corresponding structure of Figure 4.

While I have shown the U-shaped fluorescent tube 1 of Figure 1 mounted in a position depending from the sockets, it is clear from the description thus far given that the tube will remain in the sockets even if it is mounted in any position other than that illustrated in Figure 1. For instance, in Figure 8 I have illustrated the tube 1 as extending horizontally from the sockets 10-10. At this time the weight of the tube tends to swing the tube downwardly with respect to the sockets. This is resisted by the spring clips 16 which embrace the sockets and which extend into the slots 9 of the cap 3. The tube cannot fall downwardly through the slots 11-11 in the socket 10 because the prongs 8 of the tube rest in the parts 12-12 of the slots 11. In order to remove the tube from the sockets it is first necessary to remove the spring clips 16.

In Figure 9 I have shown the principles of the present invention as applied to a tube of a curvature less than 180°, in this instance a tube curved through an arc of approximately 90°. The individual sockets 10-10 are mounted in a wall in the manner indicated in Figure 4 or in Figure 6, each socket being individually adjustable. A clip 16 embraces each socket and locks the corresponding end of the tube to the socket so that no gravitational forces can cause removal of the tube from the two sockets. If the tube is slightly too long or too short for the normal distance between the sockets, the two sockets may be tilted towards or away from each other and then locked to the corresponding ends of the tube by the clips 16-16.

In compliance with the requirements of the patent statutes I have here shown and described a preferred embodiment of my invention. It is, however, to be understood that the invention is not limited to the precise construction here shown, the same being merely illustrative of the principles of the invention.

What I consider new and desire to secure by Letters Patent is:

1. A glow discharge device comprising a sealed tube, a cap secured on the end of the tube, a plurality of prongs projecting from the cap for extending circuit connections to the tube, and means for facilitating securing the tube against removal from a socket, said means comprising a pair of clip-receiving perforations in the cap and 180° apart.

2. In combination with a glow discharge device having a plug-in type terminal at an end thereof, a socket into the front of which the terminal extends to establish circuit connections with the terminal, and a releasable clip extending completely across the back and sides of the socket and with the end of the clip engaging the end of the glow discharge device for holding the device 78

and the socket together against separating movement in a direction lengthwise of the device.

3. In combination, a glow discharge device comprising a tube bent so that the longitudinal axes of the ends thereof are spaced apart, a terminal cap secured to the tube at each end thereof, a pair of sockets for receiving the caps and extending circuit connections to the device, each socket including a mass of solid insulation and contact making means therein, a supporting structure on which the sockets are mounted, means securing the sockets to the structure and permitting relative movement of the sockets with respect to one another to equalize the distance between the sockets to the distance between the terminal caps, each of said caps having at least one clip-receiving slot therein, and a clip securing the cap to its associated socket, said clip extending into said slot.

4. In combination, a pair of cooperating sockets adapted to receive and support the ends of a glow discharge tube between them, each socket including a mass of solid insulation and contact making means therein, a resilient support for at least one of the sockets to allow a limited movement of that socket towards the other socket, a glow discharge device comprising a tube having a terminal cap secured to each end thereof, said cap having terminal projections extending therefrom and insertable into said sockets, said tube being bent so that the center of gravity of the device is substantially spaced from a straight line joining the centers of the terminal caps, and a clip embracing at least one of the sockets with the ends of the clip hooked to the terminal cap associated with said socket to hold the socket and the tube against separating.

5. In combination, a pair of spaced cooperating sockets adapted to receive and support the ends of a glow discharge device between them, each socket including a mass of solid insulation and contact making means therein, and a rocking support for the mass of insulation of at least one of the sockets permitting a rocking movement of the complete socket with respect to the other socket to bring it closer to or further from the other socket to compensate for variations in the distance between the ends of different glow discharge devices.

6. In combination, a pair of cooperating sockets adapted to receive and support plug type ends of a glow discharge device between them, each socket including a mass of solid insulation and contact making means therein, a rocking support for at least one of the sockets permitting a rocking movement thereof to bring it closer to or further from the other socket to compensate for variations in the distance between the ends of different glow discharge devices, and means for locking the two sockets and the ends of a glow discharge device against separation in a direction axially of the plug ends of a device whereby the sockets support the device and the device maintains the sockets the requisite distance apart determined by the distance between the ends of the device.

7. In combination, a glow discharge device comprising a sealed U-shaped tube having plug-in type terminals at the opposite ends thereof, spaced sockets for receiving the terminals of the tube, and means for locking the terminals of the tube in the sockets and holding the tube against lengthwise movement out of the sockets, said means comprising a pair of clips each extending

completely across the back and sides of a socket and the free ends of each clip engaging the device.

8. In combination with a glow discharge device having at the end thereof a prong plug-in type terminal, means for supporting the device and establishing electric connections thereto, said means comprising a socket into which the prong terminal is movable and from which it is retractable by a movement longitudinally of the prong, and means for releasably locking said device against such longitudinal movement, said last means comprising a clip carried by the socket and

5 hooked to the glow discharge device and including a part extending from the socket to the device in a direction lengthwise of the prong and held by the socket against movement in a direction having any substantial component lengthwise of the prong and with the end of the said lengthwise extending part of the clip terminating in a clip part that extends radially towards the central axis of the device and engages the device to hold the prong against movement lengthwise of the prong.
